UNITED STATES PATENT OFFICE.

IDA M. JOSEPH, OF CHICAGO, ILLINOIS, ASSIGNOR TO SOL. H. SHONINGER, OF CHICAGO,
ILLINOIS.

DIAPER-COVER.

1,201,307.

Specification of Letters Patent. Patented Oct. 17, 1916.

Application filed May 27, 1915. Serial No. 30,724.

To all whom it may concern:

Be it known that I, IDA M. JOSEPH, a citizen of the United States of America, residing at Chicago, in the county of Cook and State of Illinois, have invented certain new and useful Improvements in Diaper-Covers, of which the following is a specification.

My invention relates to a diaper cover or protector for infants and has for its chief objects the proper ventilation and adjustability of the same.

A further object of my invention is to provide a garment which is easily attached to and removed from the body and is easily washed.

In diaper covers as hitherto proposed, it has been customary to make them out of a single piece of waterproof material and constructed and adapted to be used in such a way as to completely inclose that portion of the infant's body to which they were applied. Such diaper covers have been seriously objected to by physicians and others because they made the infant too hot, as little air could penetrate the waterproof material to the parts covered. By my improved construction proper ventilation is provided for without sacrificing the protective feature of the earlier diaper covers.

The novel features of my invention will be pointed out in the claim annexed hereto.

In the accompanying drawings Figure 1 is a perspective view of one form of my invention and Fig. 2 is a perspective view of a modified form.

Referring to Fig. 1 of the drawings, 1 is a one-piece diaper cover which is preferably made of waterproof material and is loose-fitting throughout. When open it is substantially flat, so that when it is on the child it does not conform closely to the body. It is wide at the bottom and preferably tapers inwardly toward the top. The diaper cover 1 is composed of a front and a rear portion 10 and 11 respectively, continuous at the crotch 6, but separated a substantial distance from each other at the sides when in position upon the child, providing openings 2 at the sides of the legs. The side edges of the front and rear portions run substantially parallel to each other the entire length and between these side edges are connections such that the cover is held together in position on the child and whereby the separated

edges will provide ventilating spaces at the openings 2 for the cover. These connections, as shown in the drawing, may be in the form of elastic bands 3 between the side edges and extending across the openings 2. 60 The lower ends may be connected by pieces of non-elastic cord or tape 4, tied together as in Fig. 1, or elastic bands may be used at the lower ends as shown in Fig. 2, and similar to the aforementioned bands 3. The bands 3 are preferably detachably connected at one end to either the front or rear portion of the cover by snap fasteners or other fastening means 5 and permanently attached at the other end to the opposite portion. It will be seen from the drawings that the connections between the front and rear cover are such as to provide openings with substantially parallel sides, but tapered slightly so as to be a trifle narrower at the 75 bottom than the top. This is brought about in part by the adjustable tie strings 4 at the bottom. This gives proper ventilation and at the same time tends to prevent leakage of moisture at the bottom. The crotch 6 is 80 preferably wide and straight, adding to the loose fit and assisting in the ventilation. In the form shown in Fig. 1 the crotch is permanently closed and acts as a hinge on which the front and rear portions are swung 85 away from each other when the cover is opened. There are open spaces between the crotch and the side edges through which the legs of the child extend. A cord or tape 8 at the rear of the cover is an additional 90 means of adjustment for the waist band.

In addition to proper ventilation, it will be seen the construction affords means for readily opening the cover for removal and enables it to be spread out flat for cleaning. 95

In the modified form of diaper cover, shown in Fig. 2, the ventilating openings 2 and elastic bands 3 are provided at one side only of the diaper covers. In this case I prefer to make the front and rear portions 100 of the diaper cover detachable also at the crotch portion 6 and normally held together by a snap fastener or fasteners or other fastening means 9. In other respects the diaper cover is the same as that of Fig. 1. 105

The diaper cover of my invention is self supporting and is easily washed and its construction permits of proper ventilation therethrough, allows the garment to be automatically adjusted to whatever position 110

the body may take and makes its attachment to and removal from the body very easy.

I do not wish to limit myself to the exact construction herein described and illustrated as modifications could be made which would not depart from the spirit of my invention.

What I claim as new and desire to secure by Letters Patent of the United States is:

10 A one-piece waterproof diaper cover which is substantially flat when in open position and adapted thereby to fit loosely on the body when in its closed position, and cover comprising a front and a rear portion 15 and provided with open spaces on each side of the center at the extremities of the crotch to form leg openings, the side edges of the

front and rear portions being separated a substantial distance from each other the greater part of their length and adapted to 20 be brought close together at their lower ends, when in position on the child, and connections between said front and rear portions for holding the cover together in position whereby the separated side edges will 25 provide ventilating spaces for the ventilation of the interior of the cover.

In witness whereof I have hereunto set my hand this 7th day of May 1915.

IDA M. JOSEPH.

Witnesses:

GEO. CHRISTENSON,
ELIZABETH V. HANNON.

It is hereby certified that in Letters Patent No. 1,201,307, granted October 17, 1916, upon the application of Ida M. Joseph, of Chicago, Illinois, for an improvement in "Diaper-Covers," an error appears in the printed specification requiring correction as follows: Page 2, line 13, claim, for the word "and" read *said*; and that the said Letters Patent should be read with this correction therein that the same may conform to the record of the case in the Patent Office.

Signed and sealed this 21st day of November, A. D., 1916.
